READING PROJECTOR

Bruce L. Elle and John C. Haelen, Rochester, N. Y., assignors to Eastman Kodak Company, Rochester, N. Y., a corporation of New Jersey

Application March 18, 1954, Serial No. 29,595

Term of patent 14 years

(Cl. D61—1)

Fig. 1

Fig. 2

Fig. 3**To all whom it may concern:**

Be it known that we, Bruce L. Elle and John C. Haelen, citizens of the United States of America, residing at Rochester, in the county of Monroe and State of New York, have invented a new, original, and ornamental Design for Reading Projector, of which the following is a specification, reference being had to the drawings, forming a part thereof, in which:

Fig. 1 is a side elevational view of a reading projector showing our new design;

Fig. 2 is a front elevational view thereof; and
Fig. 3 is a perspective view thereof.

We claim:

The ornamental design for a reading projector, as shown.
